(57) **CLAIM**

The ornamental design for a card holder, as shown and described.

DESCRIPTION

FIG. 1 is a rear, left and top perspective view of a card holder, showing my new design in a folded position;
FIG. 2 is a front, rear and bottom perspective view thereof;
FIG. 3 is a front perspective view thereof; shown in a closed position;

FIG. 4 is a perspective view of the card holder from FIG. 1, shown in an open position;

FIG. 5 is a front view of the card holder from FIG. 1 in a folded position;

FIG. 6 is a rear view thereof;

FIG. 7 is a left side view thereof;

FIG. 8 is a right side view thereof;

FIG. 9 is a top plan view thereof; and,

FIG. 10 is a bottom plan view thereof.

The broken lines in the drawings depict portions of the card holder that form no part of the claimed design.

1 Claim, 10 Drawing Sheets
